UNITED STATES PATENT OFFICE.

HOWARD LYON, OF GLOUCESTER CITY, NEW JERSEY, ASSIGNOR TO WELSBACK LIGHT COMPANY, OF GLOUCESTER CITY, NEW JERSEY, A CORPORATION OF NEW JERSEY.

CLUSTER INCANDESCENT GAS-LAMP.

1,202,079.

Specification of Letters Patent. Patented Oct. 24, 1916.

Continuation in part of application Serial No. 878,697, filed December 23, 1914. This application filed July 23, 1915. Serial No. 41,517.

To all whom it may concern:

Be it known that I, HOWARD LYON, a citizen of the United States, residing at Gloucester City, Camden county, New Jersey, have 5 invented a new and useful Improvement in Cluster Incandescent Gas-Lamps, of which the following is a full, clear, and exact description, reference being had to the accompanying drawings, forming part of this 10 specification, in which—

Figure 1 is a side elevation showing one form of my invention. Fig. 2 is a similar view with the upper portion in vertical section. Fig. 3 is a cross section on the line 15 III—III of Fig. 2. Fig. 4 is a cross sectional view on the line IV—IV, Fig. 2, looking downward, and Fig. 5 is a perspective view of the sleeve member.

My invention relates to cluster incandescent gas burners, and is particularly designed for cluster burners of the inverted type, though it may be used with upright burners.

In these cluster burners considerable difficulty has been experienced in insuring the ignition of the mixture of gas and air issuing from each of the burner tips; particularly if one of the mantles of the cluster is injured or absent. The ordinary pilot light 25 will not insure ignition of all of the burners; and the object of my invention is to insure such ignition, even though a mantle is broken or destroyed.

To that end the invention consists in providing an igniting flame or flames to which a mixture of gas and air is supplied, these flames being suitably positioned to ignite the mixture issuing from the various burner tips. In the preferred form, I provide an 35 igniter surrounding the mixer tube and fed with mixture therefrom, the igniter flame or flames being arranged so as to insure ignition of the mixture issuing from the burner tips.

In the drawings, in which I show my invention applied to an inverted incandescent cluster lamp, 2 is the gas supply pipe, 3 a control valve, and 4 the usual hood having air inlets leading to the Bunsen tube 5. This 50 vertical Bunsen tube is preferably provided with a lining sleeve 6 which I prefer to form as shown in Fig. 2 with a bore which decreases in diameter toward its straight

central portion, and then increases in diameter upwardly. This, of course, may or may not be used, as desired. 55

At the top of the mixer tube is a manifold 7 having a central socket portion 8 which fits telescopically over the upper end of the mixing tube, this socket portion preferably having prick punch indentations to limit the telescopic engagement. From the manifold 7 extend outwardly and downwardly directed burner arms 9 to the depending ends of which are secured the 60 burner tips 10 supporting mantles 11. 65

12 indicates the usual pilot light tube, which may or may not be used.

In order to ignite the mixture issuing from the several burner tips, I provide 70 means forming an igniter flame or flames around the mixer tube and preferably at or adjacent to the level of the mouths of the burner tips. In the form shown, this igniter is formed by a surrounding sleeve or skirt 75 13, the lower part of which is of larger diameter than the external diameter of the mixing tube, forming an annular cavity which communicates with the mixer tube through holes 14. This sleeve may be held 80 in place in any desired way, as by indenting it and the burner tube when the parts are in place, as shown at 15. This skirt or ring will provide an annular flame fed by the mixture and ignited by the pilot light, which 85 will burn continuously during the operation of the lamp. However, even this annular flame in some cases does not absolutely insure ignition of the mixture issuing from every tip, in case a mantle is injured or destroyed. 90 To further insure such action I provide the holes or jet openings 16 below the lower edge of the sleeve and preferably registering with the burner tips. These jet openings are preferably the same in number 95 as the burner tips and placed adjacent to them so that the jets of flame projecting through these holes will insure ignition at each burner tip.

In the use of the apparatus the pilot 100 light, of course, burns continuously, and when the gas is turned on the mixture of gas and air formed in the mixer tube will flow to the burner tips and at the same time will issue into the annular cavity around the 105 mixer tube and be ignited by the pilot flame.

This annular flame will light the lower jets, and the combined flames insure the ignition of the mixture issuing from each burner tip.

17 indicates a cylindrical impedance placed in the manifold and through which the mixture flows to the burner arms.

The advantages of my invention result from insuring the ignition of all of the jets of mixture issuing from the various burner tips, under all conditions. This is particularly important as this burner may be and often is used without surrounding glassware, and is more or less subjected to side drafts. The system is of advantage whether 15 a pilot light is used or not, inasmuch as a match applied near the burner will cause all the burners to ignite.

This ignition system may be applied to cluster incandescent lamps of other forms 20 and the mixer igniting flames may be formed by other structures or parts than those shown, without departing from my invention, since I consider myself the first to provide an ignition flame or flames independent 25 of the burner tips fed from the mixture and adapted to light the mixture issuing from said burner tips.

This application is a continuation in part of my copending application Serial No. 30 878,697, filed December 23, 1914.

I claim:

1. An incandescent gas lamp of the cluster type having a plurality of burner tips and a mixing tube arranged between said 35 tips, said tube having an exterior mixture distributing channel, and an opening connecting its interior with said channel, substantially as described.

2. An inverted incandescent gas lamp of 40 the cluster type having a plurality of burner tips and a mixing tube arranged between said tips, said tube having an exterior mixture distributing channel, and an opening connecting its interior with said channel, together with a pilot light arranged to ignite 45 the gas in said channel, substantially as described.

3. An incandescent gas lamp of the cluster type having a plurality of burner tips 50 and a mixing tube arranged between said tips, said tube having means thereon forming a mixture distributing channel adjacent to the burner tips, and means for supplying mixture to said channel directly from the mixing tube and independently of the tips, substantially as described.

4. An incandescent gas lamp of the cluster type having a plurality of burner tips and a mixing tube arranged between said 60 tips, said mixing tube having a ring or sleeve member on the upper portion thereof and said member having therein a mixture distributing channel surrounding the mixing tube and opening adjacent to the burner 65 tips, together with means for supplying

mixture to said channel independently of the burner tips, and a pilot light arranged to effect the ignition of the mixture in said channel, substantially as described.

5. An inverted incandescent gas lamp of 70 the cluster type, having a plurality of burner tips, and a mixing tube arranged between said tips, there being an open bottom mixture distributing channel surrounding the mixing tube adjacent to said tips, and means 75 for supplying mixture to said channel from the mixing tube, substantially as described.

6. An incandescent gas lamp of the cluster type, comprising an upright mixing tube carrying a plurality of depending burner 80 tubes whose tips are adjacent to said mixing tube, means for supplying gas and air to said tube, there being an open bottom distributing channel surrounding the mixing tube adjacent to said tips, and means for 85 supplying a mixture of gas and air to said channel independently of the burner tubes, substantially as described.

7. A cluster burner for incandescent gas lamps having a vertically extending mixer 90 tube, means for supplying a mixture of gas and air to said tube, a series of burner tips around said tube, a mixture container around the mixer tube arranged to furnish a flame to light the various tips, and connections 95 arranged to supply mixture to said container independent of the burner tips, substantially as described.

8. A cluster incandescent gas lamp having a central mixer tube, a mixture container 100 around the tube inside the burner tips and arranged to maintain an annular flame of mixture to ignite the gas from said tips, and connections arranged to feed mixture to said mixture container, substantially as de- 105 scribed.

9. A cluster incandescent gas lamp having a central mixer tube, a plurality of burner tips, a mixture distributing channel around 110 said tube and receiving mixture directly therefrom independently of the burner tips, said channel being so arranged as to ignite the mixture from the various tips, substantially as described.

10. A cluster incandescent burner having 115 a central mixer tube, and a surrounding igniter arranged to receive mixture and supported on the mixer tube and a connection arranged to feed mixture to said igniter independently of the burner tips, substantially 120 as described.

11. An inverted incandescent gas lamp having a central mixing tube, a plurality of burner tips arranged in a circle about said tube, an annular igniter therefor, a pilot 125 light therefor and a connection arranged to supply mixture to said igniter independently of the burner tips; substantially as described.

12. A cluster incandescent gas lamp hav- 130

ing a mixer tube, an igniter system around the tube arranged to ignite the mixture issuing from the various burner tips, and a connection arranged to supply a mixture of gas and air to said igniter system from the mixer tube independent of the burner tips, substantially as described. 5

13. A cluster incandescent burner having a central mixer tube, a plurality of 10 burner supports, and a surrounding igniter arranged to receive mixture and supported on the mixer tube, there being a jet opening adjacent to each burner support extending through the wall of the mixing tube and below the surrounding igniter, substantially 15 as described.

14. An inverted incandescent gas lamp of the cluster type, having a plurality of burner tips and a mixer tube between them, jet

igniters for the burner tips, and a connection arranged to supply mixture to the jet igniters from the mixer tube, the tips being adjacent to the mixer tube so as to be lighted by the igniters; substantially as described. 20

15. An inverted incandescent burner of 25 the cluster type having a central mixer tube, burner tips arranged in a circle around said tube, and a plurality of jet openings communicating with the mixer tube, said openings being located between the burner tips, 30 substantially as described.

In testimony whereof, I have hereunto set my hand.

HOWARD LYON.
